UNITED STATES PATENT OFFICE.

GARRETT M. SMITH, OF FORT WORTH, TEXAS.

WRENCH.

Application filed November 13, 1926. Serial No. 148,194.

This invention relates to improvements in wrenches of the parallel jaws type in which one of the jaws is carried by a main stock and the other jaw carried by an auxiliary stock, the two jaws being maintained in parallel relation by parallel links pivotally connecting the auxiliary stock with a sleeve adjustable on the main stock. The object of the invention is to provide means for holding the sleeve in its adjustments on the main stock, said means being easily operated and permitting a quick adjustment of the jaws to meet the requirements.

The invention consists in the novel construction, combination and arrangement of parts, hereinafter described, pointed out in the appended claim, and illustrated by the accompanying drawings.

In the accompanying drawings, in which similar reference characters designate corresponding parts:

Fig. 1 is a plan view of a wrench embodying the invention,

Fig. 2 is a side elevation,

Fig. 3 is a detail view showing the main stock,

Fig. 4 is a view partly in plan and partly in longitudinal section, and

Figs. 5, 6 and 7 are sectional views on the lines 5—5, 6—6 and 7—7, respectively, of Fig. 1.

Referring to the drawings in detail, 10 designates the main stock of the implement with one end shaped to form a handle 11. 35 On the other end of the stock is formed the jaw 12 with the claw 13 seated on its face. Slidable on the main stock is the sleeve 14, the stock and sleeve being rectangular in cross-section, as to their meeting faces, so 40 that the sleeve cannot turn on the stock. Pivoted to the outer side of the sleeve are ends of the four links 15, the other ends of these links are pivoted to the auxiliary stock 16 carrying the other jaw 17 of the implement. The sleeve, links and auxiliary stock 45 are so proportioned and connected as to form a jointed parallelogram.

Each pair of links is hinged at one end to the sleeve by a pin 18 passing through 50 the ends of the links and the boss 19 on the outer side of the casing; the other end of each pair of links is hinged to the auxiliary stock by the pin 20 passing through the ends of the links and the body of the auxiliary

stock. Each pin 20 is held in place by a 55 head at one end and a cotter pin passing through the other end.

The hinged parallelogram formation of the parts comprising the auxiliary stock, the links and the sleeve slidable on the main stock serves to maintain the faces of the opposing jaws in parallel relation irrespective of the movement of the sleeve on the main stock. The rearward movement of the auxiliary stock with relation to the sleeve is 65 limited by the rear pair of links striking the abutments 21 extending from the opposite sides.

The sleeve 14 is provided with means for holding it in its adjustments on the main 70 stock. In the forward end of the outer side of the sleeve is an opening in which is seated the nipple 22. Guided in this nipple is the bolt 23 adapted to engage the sockets 24 formed in the outer side of the main stock. 75 At an intermediate part the forward boss 19 is transversely recessed and extending through the recess is the lever 25 pivoted on the pin 18 passing through the boss. The forward end of the lever extends through 80 the side of the nipple 22 and is forked to engage the neck or reduced part of the bolt 23. Between the rear end of the lever and the sleeve is interposed the coiled spring 26 under compression that normally tends to 85 press the rear end of the lever outwardly. Consequently, the front end of the lever normally tends to press the bolt 23 inwardly to engage any of the sockets 24 that may be in register with the bore of the nipple. The 90 inner end of the coil is seated in a socket in the wall of the sleeve and the other end is engaged by a lug on the under side of the lever, the spring being held against accidental displacement. The outer face of the rear 95 end of the lever is shaped to form a finger-piece so that the lever can be readily depressed to raise the bolt from engagement with a socket. By adjusting the sleeve on the main stock the opening between the jaws 100 can be regulated to meet the requirements of the work.

The claw plates 13 on the face of the jaws 12 and 17 have their respective teeth extending in opposite directions to meet the requirements of the implement used as a pipe wrench. The plate on the claw 12 has its teeth projecting forward to engage the pipe

on the forward thrust of the main stock, while the teeth of the plate on the jaw 17 project rearward to engage the pipe during the pull of the auxiliary stock during a pipe-turning operation. The claw plates are detachably mounted on the jaws so that they can be replaced when they become worn. In the face of each jaw is a longitudinal recess 27 into which fits a longitudinal projection 28 on the back of the said plate. Across the face of each jaw, at the inner end of jaw 12 and at the outer end of jaw 17, extends an abutment 29 engaging a recessed end of the claw plate to hold the plate against the thrust of the work. Each plate is held in place by a screw 30 passing through the jaw into the claw plate. To facilitate the attachment and removal of the claw plates, a screw-driver 31 is provided that is particularly shaped to fit the screw-head and when not in use is turned into the socket 32 in the end of the handle 11.

What I claim is;

In a wrench, the combination with a main stock and an auxiliary stock, having opposing jaws, of a snugly fitting sleeve of generous length slidable on the main stock, parallel links pivotally connecting the two stocks in parallel relation, said main stock having a series of sockets extending along the same, a nipple on the sleeve and opening through the wall of the sleeve to register with said sockets, a bolt having a neck and movable in the nipple to engage the sockets, a lever pivoted to the sleeve and having a forked end extending into the nipple and engaging said neck of the bolt, and a spring compressed between the other end of the lever and the sleeve to move the lever to project the bolt inwardly to engage the sockets, said lever having its outer face of the free end shaped to form a finger-piece.

In testimony whereof I affix my signature,
GARRETT M. SMITH.
